UNITED STATES PATENT OFFICE.

CHARLES E. THOMPSON, OF TROY, NEW YORK.

DESIGN FOR A BRUSH.

SPECIFICATION forming part of Design No. 37,340, dated February 14, 1905.

Application filed January 19, 1905. Serial No. 241,909. Term of patent 14 years.

To all whom it may concern:

Be it known that I, CHARLES E. THOMPSON, a citizen of the United States, residing at Troy, county of Rensselaer, State of New York, have invented a new, original, and ornamental Design for Brushes, of which the following is a specification, reference being had to the accompanying drawing, forming a part thereof.

The single figure of the drawing is a view

in perspective of a brush embodying my new, original, and ornamental design.

What I claim as new, and desire to secure by Letters Patent, is—

The ornamental design for a brush substantially as herein shown.

CHARLES E. THOMPSON.
